METHOD OF FUR DYEING

Edward Ohsman, New York, N. Y.

Application April 29, 1937, Serial No. 139,663

2 Claims. (Cl. 8—10)

This invention relates to a method and apparatus for dyeing fur skins, but more specifically, to a method and apparatus for developing shadow effects on fur skins by a process of immersion in a dye bath.

The main object of the invention resides in the provision of a simple method and apparatus whereby fur skins are shadowed or given different shades of a dye in a dye bath.

10 A further object of the invention resides in the provision of a method and apparatus whereby fur skins are given a shadowing effect by withdrawing immersed portions of fur skins in a dye bath at pre-determined intervals.

15 Another object of the invention resides in the provision of a fur skin rack cooperating with a dye vat, the said rack being suspended over the vat and being vertically adjustable and having a horizontally reciprocating movement.

20 These objects and other incidental ends and advantages of the invention will hereinafter appear in the progress of the disclosure and as pointed out in the appended claims.

The accompanying drawing shows a preferred embodiment of the rack apparatus used to immerse and agitate fur skins which are adapted to be suspended from the said apparatus.

In accordance with the drawing:

25 Figure 1 is a top plan view of the apparatus showing a series of bars or slats on a rack from which fur skins are adapted to be suspended into a dye vat.

30 Figure 2 is a side elevational view of the apparatus of Figure 1 showing the said rack as a vertically adjustable and horizontally reciprocating one.

35 Figure 3 is a front view in elevation particularly showing the means of vertical adjustability of the movable rack.

40 Figure 4 is a fragmentary view of a fur skin suitably folded and depending from a bar in the rack and being partially immersed in the dye bath.

45 Figure 5 is a plan view of a fur skin after it has been given a shadowing effect.

Before shadowing the fur skins, which is the object of the invention herein, the skins are given the usual treatment and dyed with a ground dye to a uniform color. The skins are first given the customary killing or scouring treatment of either sal soda or soda ash for two to three hours, depending on the type of skin or section to be dyed, and are then washed well in running water for about thirty minutes and then hydro-extracted. Thereafter, the customary mordant used in fur dyeing is applied to the skins, the said mordant being either potassium, dichromate, iron sulphate or copper sulphate. The skins are left in the mordant bath for sixteen to twenty hours after which they are hydro-

extracted. After the mordanting, the skins are ready to be given a ground dye. The dyes used are the ordinary type of Ursol fur dyes, the particular type of dye to be used depending upon the desired color to be effected. The usual time required for the ground dye is two to three hours. Following the application of the ground dye, the skins are hydro-extracted and stretched well.

Now the skins are ready to be given the shadowing effect, which is the object of the invention herein. The stretched skins are placed on a series of bars or slats which are preferably approximately one and one-quarter (1 1/4) inches wide and five (5) feet long and fastened thereto by any ordinary means such as thumb tacks. The skins are placed on the said slats or bars in any position depending upon the desired position of the shadow stripes. As shown in Figure 4 of the drawing, the skins are re-doubled twice with the hairs on the outside and are then placed in a straddling position thereon with the open edges projecting below the bent edge to provide for subsequent trimming. The bars with the skins fastened to them are then placed on a rack construction suspended by cables, the latter depending from pulleys in a framework which also supports a dye vat. The rack is vertically adjustable by means of the said cables relative to the dye vat and in addition is given horizontal reciprocating movement about the cables as supports to provide agitation for the rack. The cables supporting the rack are passed through a series of pulleys mounted on the framework and then secured to a drum having a ratchet and ratchet wheel cooperating therewith.

30 The rack together with the bars or slats thereon mounting the fur skins is adjusted to produce the proper width of shadow stripes by lowering the rack whereby the desired depth of the fur skins in the dye bath is obtained. The rack is kept in a swinging motion and raised at pre-determined intervals in order to produce a shadow stripe having different and merging shades thereon. For example, to produce one type of different and merging degrees of shade in a shadow stripe, the fur skins are immersed to the desired depth and kept therein for one minute while the rack is mounted in swinging motion. Thereafter the rack is raised to the extent of one notch of the ratchet; after three minutes another notch of the ratchet is raised; after seven minutes another notch of the ratchet is raised; after twelve minutes another notch of the ratchet is raised. Thereafter the rack is kept swinging for thirty minutes after which time the motion is stopped and the rack is allowed to remain in a stationary position until the desired depth of shade of the lower portion of the shadow stripe is obtained. When this point is reached, the ratchet is raised so that the skins are completely

out of the dye bath. The skins are then removed from the bars and are hydro-extracted. Following the hydro-extraction, the skins are treated in the usual way for finishing, namely: oiled, then hung to dry and finished in saw dust tumblers with maple saw dust.

The framework, the rack, the vat and the agitation and adjustment means hereinbefore mentioned are now to be described as typical of the apparatus utilized in practicing the invention herein. The framework consists of two forward and two rear vertical posts 10, 11 and 12 and 13 respectively. A lower forward and rear cross bar 14 and 15 are suitably joined to the upright posts while the upper forward and rear cross bar 20 and 21 are similarly joined to the posts. Lower longitudinal members 16, 17 and upper longitudinal members 18, 19 are secured to the posts at the corresponding cross bars. The framework is provided with suitable reinforcing brackets 23, 22, 24 and 25 at the forward side, and similar brackets not shown in the drawing on the rear side. Reinforcing brackets 26, 27 and 28 and 29 are also provided at the outer lateral side of the framework, and similar brackets not shown in the drawing on the lateral inner side. The cross piece 30 is adapted to be secured across the lower longitudinal members 16 and 17 at the under edges and intermediate the length of the said members with appropriate reinforcing brackets 31, only one of the said brackets being shown in the drawing.

A dye vat is supported on the longitudinal members 16, 17 and cross members 14 and 15 of the lower part of the framework, the said dye vat having forward and rear walls 32, 33 and longitudinal side walls 34 and 35. The floor 36 for the vat is suitably and water-tightly joined to the walls 32, 33 and 34 and 35 as best shown in Figure 2. A series of parallel or supporting strips 37 are secured to the under surface of floor 36 and are adapted to rest on the upper surface of the lower longitudinal members 16 and 17.

Adapted to be raised, lowered and agitated in the dye vat is a fur skin rack attached to cables, the said cables passing downwardly through overhead pulleys attached to the framework and proceeding from a drum also mounted on the framework, the said drum having a ratchet wheel and ratchet associated therewith. The rack is comprised of two two-ply longitudinal members shorter than the length of the dye vat to permit agitation therein and two two-ply transverse members slightly shorter than the width of the dye vat. Thus, 59-60 and 62 and the underly thereof, 61 shown in the drawing constitute the longitudinal members of the rack while 63-64 and 65-66 constitute the transverse members thereof.

60 The pulley frames and pulleys therein above-mentioned are secured to the under-surface of upper longitudinal members 18 and 19. Thus, pulley frames and pulleys 38, 39 and 42 secured to the under surface of upper longitudinal member 19 carry cables 45 and 46 secured to the longitudinal double-ply member 59-60 of the rack by means of turn buckles 69 and 70. The cables proceed downwardly from pulley 42 onto a drum 57 which is secured to a mounting piece 11' being affixed to the post 11. Pulleys 41, 48 and 43 and 44 lead cables 47 and 48 from the opposite longitudinal member of the rack to the drum 57. Cables 47 and 48 are similarly se-

cured to the rack at the opposite longitudinal member thereto by means of turn buckles, such as 70' and another not shown in the drawing.

The upper piles of the longitudinal members of the rack are provided with transversely aligned recesses 68 disposed inwardly of the outer edges. The said recesses 68 are in alignment and are in parallel to accommodate a series of bars or slats 67, each of which is adapted to have secured thereto, as has been before mentioned, a fur piece which is intended to be immersed in the dye vat. The bars 67 are removable from recesses 68 for the usual reasons of removing the fur skins from the rack and securing new fur skins to be shadowed.

Attached to drum 57 is a gear 51 and a ratchet wheel 58, the said gear 51 being rotated by means of a pinion 52, the said pinion 52 being mounted on a shaft 56 affixed to the panel 11'. The ratchet wheel 58 is provided with a ratchet 53 to prevent counter-revolution of the said ratchet wheel. The drum 57 is also provided with a shaft 49 affixed to the panel 11'. Pinion 52 is provided with an operating lever 54 to rotate the same while lever 55 operating on shaft 56 serves as a stopping nut for the lever 54.

Figure 4 shows a skin 75 as it is mounted on a bar 67 and is immersed in the dye bath. The skin 75 shown re-doubled twice is adapted to give a series of parallel stripes a shadowing effect 30 when in out-stretched position. Any other type of mounting of fur skins 75 on slats 67 is feasible to produce other effects. It is to be observed that when the rack with the fur skins thereon is first immersed in the dye bath the skins are lowered 33 to a greater depth than the width of the stripe desired in order to eliminate the possibility of obtaining a clear line of demarcation at the upper limit of the stripe.

The rack is given a horizontally reciprocating motion by any known method; thus intermediate the width of the rear transverse member 63-66 of the rack is secured an upright bar 71. Slidably engaging with the said upright bar 71 is a connecting arm 72 which is pivotally connected 45 to an oscillating arm 73. The agitation of the rack causes the fur skins 75 to be thoroughly saturated with the dye solution in the vat.

I wish it understood that minor changes and variations in the steps of the method outlined above may be resorted to without departing from the spirit of the invention and that minor changes and variations in the construction of the apparatus utilized in the practice of the method may also be resorted to without departing from the spirit of the invention and without departing from the scope of the appended claims.

I claim:

1. In a method of producing merging shadowing effects on a fur skin, the step of folding over 60 the skin with the hair outwardly disposed, immersing the skin in a dye bath and simultaneously agitating the skin while immersed and raising portions of the skin out of the bath successively and at different time intervals during 65 the said agitation.

2. In a method of producing merging shadowing effects on a fur skin, the step of immersing the skin in a dye bath and simultaneously agitating the skin while immersed and raising portions 70 of the skin out of the bath successively and at different time intervals during the said agitation.

EDWARD OHSMAN.
